US00D914615S

(12) **United States Design Patent** (10) **Patent No.:** **US D914,615 S**
Yi (45) **Date of Patent:** **** Mar. 30, 2021**

(54) **CONTROLLER APPARATUS FOR VEHICLE LIGHT**

(71) Applicant: **Yong Guk Yi**, Corona, CA (US)

(72) Inventor: **Yong Guk Yi**, Corona, CA (US)

(**) Term: **15 Years**

(21) Appl. No.: **29/722,068**

(22) Filed: **Jan. 26, 2020**

(51) LOC (13) Cl. **14-03**

(52) U.S. Cl.

USPC **D13/168**

Primary Examiner — Selina Sikder

(74) *Attorney, Agent, or Firm* — Alexander Chen, Esq.

(57) **CLAIM**

The ornamental design for a controller apparatus for vehicle light, as shown and described.

DESCRIPTION

FIG. 1 is a front perspective view of the controller apparatus for vehicle light showing my new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a back perspective view thereof.

1 Claim, 5 Drawing Sheets
